UNITED STATES PATENT OFFICE.

GEORG F. RUDOLF BLOCHMANN, OF KIEL, GERMANY.

NAVAL ARCHITECTURE.

SPECIFICATION forming part of Letters Patent No. 775,889, dated November 22, 1904.

Application filed September 14, 1903. Serial No. 173,104. (No model.)

To all whom it may concern:-

Be it known that I, GEORG FRIEDRICH RUDOLF BLOCHMANN, a subject of the German Emperor, and a resident of Kiel, Germany, 5 have invented new and useful Improvements in Naval Architecture, of which the following is a full, clear, and exact description.

Up to the present time no armor has been discovered which will efficiently protect marine vessels against the disastrous effects of submarine explosions. There is no doubt that such protection becomes more necessary as the weapons for under-water attack, such as fixed and movable torpedoes and submarine 15 boats, become more highly developed and effective for offensive work.

It is impracticable to build up the entire outer skin of a ship with heavy armor-plate, as has partly and with excellent results been 20 done above water, to shield it against the vigorous attack of heavy ordnance, because the thickness of the armor required to resist the force of large quantities of explosive material discharged against the sides or bottom of the 25 vessel must necessarily increase the weight of the vessel beyond the limit of practicability.

My pyrodynamic investigations, partly given to the public in a "Treatise upon Explosives Under Water" and published in the 30 *Marinerundscha*u, 1898, book 2, page 197, were the first to consider systematically the peculiar characteristics of an under-water explosion and definitely to determine the consequent effect upon its immediate surroundings.

35 Among other things there have been deduced from these investigations that the powerful effect of an under-water explosion diminishes very rapidly from points somewhat removed from the center of effort, which is the surface 40 of the explosive. If, therefore, means be employed to prevent the explosive effort from coming into direct contact with the armored skin—that is to say, means by which the armored skin may be maintained at a certain 45 distance from the explosive—then the vessel may be clad with a medium thickness of armor throughout its bottom and sides without detracting seriously from its effectiveness at other points.

50 This invention is based upon these premises;

and it consists in giving to the ship several (at least two) complete walls or bottoms under water, of which, however, not the outer skin, but perhaps one of the inner skins, may be armor-clad.

55

This specification is an exact description of several forms of my invention, while the claims define the actual scope thereof.

Reference is to be had to the accompanying drawings, forming a part of this specification, 60 in which similar characters of reference indicate corresponding parts in both the views.

Figure 1 is a cross-section showing my improved structure as applied to a modern battle-ship, and Fig. 2 is a cross-section showing 65 the improvements applied to a modern cruiser.

The water-tight compartments *a*, formed by the several bottoms *b*, *c*, and *d*, supported and separated by the ribs and longitudinal girders *e* of the frame, may be filled with air, 70 liquids, and with such solid matter as bits of cork or corn-pith, or a combination of any of these, for the purpose of weakening the effect of the exterior explosions upon the real protective armor lying inside of and behind them. 75 That the proper influence of the intermediate bottoms *b*, *c*, and *d* upon the exterior explosive effort may become especially effective the opposite girders and ribs of the several separate floors should be suitably overlapped. 80 Moreover, in order to afford a strong connection for the outboard side armor which is intended to resist the attack of heavy artillery a horizontal bulkhead *f* may be suitably constructed at a certain height from the side of 85 the ship, and thus developed into armor. The bulkhead may at the same time become a solid support for the outboard armor *g*, inasmuch as by stiffening it up by brackets it may be drawn down and out, so as to form to a degree a foundation upon which the outboard armor may rest. In this manner the whole vertical side armor may be worked outside, whereby a more stable and unbroken framing without bends will become possible. The possible disadvantages of any increased friction 90 may be avoided if the under side edge be brought up to and attached to the running-lines. The side armor being applied in this manner, and especially if it be desired to lessen 95 100

the danger from fire and splinters, the wooden support may be the more readily eliminated than in the present method of attaching it in a niche artificially constructed in the side 5 of the ship. Attention must also be especially directed to the fact that a protective armor built up according to the above conditions must also become a very advantageous protection against other submarine dangers, such as sunken reefs, derelicts, &c. 10 Again, a ship constructed according to my invention will be much easier to keep watertight, and the danger from leaking by the working of the ship in a seaway, the piercing 15 of the shell by a projectile, or other similar accidents is reduced to a minimum.

The transition of the inner armor *d* of the bottom to the sides of the ship instead of being curved, as shown in the drawings, may 20 also be angular, wherein the connection would be effected by a heavy armor-bracket, which would permit of an easier and cheaper production of the armor.

The protective deck *h* is so constructed 25 that it rests upon the heavy beams and is worked down to the upper edge of the triple bottom *d*, thus providing a better double protective behind the vertical side armor than is at present the custom.

30 Various changes in the form, proportions, and minor details of my invention may be resorted to at will without departing from the spirit and scope thereof. Hence I consider myself entitled to all such changes as may lie 35 within the intent of my claims.

Having thus described my invention, I claim as new and desire to secure by Letters Patent—

1. A marine vessel, provided with three or more spaced bottom walls forming a plurality 40 of superimposed compartments, of which one or more of the inner walls is armor-clad, whereby to protect the vessel against the

effects of submarine explosions or other violent shocks, said walls being turned upwardly around the sides of the ship-bottom, and a 45 horizontal bulkhead connecting said walls together at their upper sides.

2. A marine vessel, having a plurality of spaced bottoms forming separate compartments, and longitudinal girders and ribs in said 50 compartments, the girders of the upper compartments being intermediate of the girders of the lower compartments.

3. A marine vessel, having a plurality of spaced bottom walls forming superimposed 55 compartments, horizontal bulkheads extending out from the inner bottom wall, and vertical outboard armor mounted on the outer portions of said bulkheads and supported thereby.

4. A marine vessel provided with a plurality of spaced bottom walls forming superimposed compartments, said walls being turned upwardly around the ship-bottom, a horizontal bulkhead connecting said walls together at their upper sides, and a protective 65 deck supported around its edges upon the inner side of said bulkhead.

5. A marine vessel provided with a plurality of spaced bottom walls forming superimposed compartments, said walls being turned upwardly around the ship-bottom, a horizontal bulkhead connecting said walls together at their upper sides and projecting 70 outwardly beyond the outer wall to form a 75 foundation for the outboard armor.

In testimony whereof I have signed my name to this specification in the presence of two subscribing witnesses.

G. F. RUDOLF BLOCHMANN.
